United States Patent Office

Des. 197,759
Patented Mar. 24, 1964

197,759

SOAP HOLDER

Don Schreckengost, East Liverpool, Ohio, assignor to Federal Ceramics Corporation, Mineral City, Ohio, a corporation of Ohio

Filed Apr. 16, 1962, Ser. No. 69,726

Term of patent 14 years

(Cl. D4—3)

Fig. 2

Fig. 1

Fig. 3

FIG. 1 is an isometric view of a soap holder embodying my new design;

FIG. 2 is a top plan view thereof;

FIG. 3 is a front elevational view thereof; and

FIG. 4 is a side view thereof.

The side not shown is like the side shown, and the rear is flat and plain.

I claim:

The ornamental design for soap holder, as shown and described.
